(57) **ABSTRACT**

A nestable crate includes a base, a pair of opposed side walls extending upward from the base, and a pair of opposed end walls extending upward from the base. The side walls and end walls include an upper band portion and a lower portion connecting the base to the upper band portion. A center structure extends from one of the end walls to the other of the end walls. The center structure includes a plurality of center column portions extending down to the base. The center structure further includes an upper handle portion partially defining a handle opening therebelow. The upper handle portion includes spaced-apart handle side walls defining openings upward of the crate.

BEVERAGE CRATE WITH HANDLE

BACKGROUND

Nestable beverage crates typically have side walls and end walls extending upward from a base. Handle openings are formed in the opposed end walls. Depending on the size of the bottles intended to be stored in the crate, the crate may hold a number of bottles. For single-serving size bottles, the crate typically stores 20-24 bottles.

Sometimes, a delivery person or stock person must remove the bottles from the crate and place them on a shelf for individual sale, such as in a refrigerator in the store.

SUMMARY

A nestable crate includes a base, a pair of opposed side walls extending upward from the base, and a pair of opposed end walls extending upward from the base. The side walls and end walls include an upper band portion and a lower portion connecting the base to the upper band portion. A center structure extends from one of the end walls to the other of the end walls. The center structure includes a plurality of center column portions extending down to the base. The center structure further includes an upper handle portion partially defining a handle opening therebelow. The centered handle opening permits a user to hold the crate with one hand while unloading the bottles from the crate with the other hand.

The upper handle portion may include spaced-apart handle side walls defining openings upward of the crate.

BRIEF DESCRIPTION OF THE DRAWINGS

- FIG. 1 is a perspective view of a beverage crate.
- FIG. 2 is a side view of the crate.
- FIG. 3 is an end view of the crate.
- FIGS. 4 and 5 are bottom perspective views of the crate.
- FIG. 6 is a top view of the crate.
- FIG. 7 is a bottom view of the crate.
- FIG. 8 shows the crate nested with an identical crate.
- FIG. 9 is a side view of the crates of FIG. 8.
- FIG. 10 is an end view of the crates of FIG. 8.
- FIGS. 11 and 12 show the crates of FIG. 8 broken away along the longitudinal centerline.
- FIGS. 13 and 14 show the crates of FIG. 8 broken away along a lateral centerline.
- FIG. 15 shows the crate loaded with a plurality of containers.

- FIG. 17 is an end view of the crate and bottles.
- FIG. 18 is a top view of the crate and bottles.

DETAILED DESCRIPTION OF A PREFERRED EMBODIMENT

A beverage container or crate 10 is shown in FIGS. 1-18. Referring to FIG. 1, the crate 10 includes a base 12 and side walls 14 extending upward from side edges of the base 12. End walls 16 (or short walls) extend upward from opposite ends of the base 12. The base 12 includes a plurality of base walls 13 each for supporting a beverage container thereon. The end walls 16 and side walls 15 include an upper band portion 18 and a lower portion 20. The lower portion 20 includes a plurality of columns 26 connecting the upper band portion 18 to the base 12 and spaced inward of the upper band portion 18, such that the lower portion 20 could

be nested between the upper band portions 18 of an identical crate nested therebelow. The columns 26 project into the interior of the crate 10 to define bottle-receiving pockets on the base 12. In the example shown, twenty-four bottle-receiving pockets are defined in the crate 10. Corner columns 28 connect the upper band portion 18 to the base 12 at the corners of the crate 10. The end walls 16 and side walls 14 are integrally molded with the base 12 as a single molded piece of plastic.

- 10 A center structure 30 extends from the center of one end wall 16 to the center of the opposite end wall 16. The center structure 30 divides the crate 10 into two equal halves and projects above the upper band portion 18. The center structure 30 includes a plurality of column portions 32 extending down to the base 12. The center structure 30 includes an upper handle portion 34 at its center, which is the highest point on the center structure 30 and on the crate 10. The upper handle portion 34 is cored from above and is thus open upward with a pair of ribs 38 formed in the upper handle portion 34. The upper handle portion 34 is open upward between the ribs 38 and outward of the ribs 38. By being cored from above, a smooth, solid surface is provided at the bottom of the upper handle portion 34 for contacting a user's hand. A handle opening 36 is defined below the upper handle portion 34 for receiving a user's hand. A lower handle wall 37 is spaced below the upper handle portion 34 and defines the handle opening 36 therebetween. The upper handle portion 34 includes spaced apart handle side walls 39. The ribs 38 extend from one handle side wall 39 to the other.
- 15 The upper portion of the side walls 14 and end walls 16 includes alternating recesses 40 for receiving a bottle and projections 42 partially separating and defining adjacent bottle receiving pockets. Similarly, an upper portion of the center structure 30 includes alternating recesses 44 and projections 46 similarly defining bottle receiving pockets.
- 20 The entire crate 10 as described is integrally molded as a single molded piece of plastic.
- 25 FIG. 2 is a side view of the crate 10. As shown, the upper handle portion 34 and a small portion of the handle opening 36 are higher than the upper band portion 18.
- 30 FIG. 3 is an end view of the crate 10. As shown, the column portions 32 of the center structure 30 extend down to different halves of the base 12, separated by a center gap. In each half of the base 12, the base walls 13 are connected
- 35 to one another by rib structure, but there are no ribs connecting the halves of the base 12 or the column portions 32 below the upper band portion 18. This is shown more clearly in the bottom perspective views of FIGS. 4 and 5.
- 40 FIG. 6 is a top view of the crate 10. FIG. 7 is a bottom view of the crate 10.
- 45 FIG. 8 shows the crate 10 nested with an identical crate 10. The lower portions 20 of the side walls 14 and end walls 16 of the upper crate 10 are received within the upper band portion 18 of the lower crate 10. This reduces the height and volume occupied by the crates 10 when empty. As shown, the center structure 30 of the lower crate 10 nests within the center structure 30 of the upper crate 10, between the column portions 32. FIG. 9 is a side view of the crates 10 of FIG. 8. FIG. 10 is an end view of the crates 10 of FIG. 8.
- 50 FIGS. 11 and 12 show the crates 10 of FIG. 8 broken away along the longitudinal centerline. This shows more clearly how the center structure 30 of the lower crate 10 is received within the center structure 30 of the upper crate 10. The upper handle portion 34 of the lower crate 10 is received between the column portions 32 of the upper crate 10, below the handle opening 36. Referring to FIG. 12, an upper handle wall 48 is spaced above the lower handle wall 37. The upper

handle wall 48 is the lower surface of the upper handle portion 34 and provides the smooth, solid, non-ribbed lower surface that contacts the user's hand. The ribs 38 extend upward from the upper handle wall 48. End handle walls 50 extend from ends of the lower handle wall 37 upward to the upper surface of the upper handle portion 34. The upper handle wall 48 extends from one end handle wall 50 to the other. Notably, all of the structure of the handle, the upper handle portion 34, the ribs 38, the upper handle wall 48, the lower handle wall 37 and the end handle walls 50, connect the two halves of the crate 10.

FIGS. 13 and 14 show the crates 10 of FIG. 8 broken away along a lateral centerline. Again, the center structure 30 of the lower crate 10 is received within the center structure 30 of the upper crate 10. The upper handle portion 34 of the lower crate 10 is received between the column portions 32 of the upper crate 10, below the handle opening 36.

FIG. 15 shows the crate 10 loaded with a plurality of containers, namely 250 mL plastic beverage bottles 80 (although other containers or other items could also be used). The bottles 80 are supported on the base 12 and held between the side walls 14 and the end walls 16. Each bottle 80 is supported on a different base wall 13. The center structure 30 separates the bottles 80 into each half of the crate 10. The bottles 80 are taller than the center structure 30, such that a similar loaded crate 10 stacked thereon would be supported directly on the bottles 80.

FIG. 16 is a side view of the crate 10 and bottles 80 of FIG. 15. The uppermost surface of the upper handle portion 34 is lower than the uppermost surface of the bottles 80 and lower than the bottle caps. The handle opening 36 below the upper handle portion 34 is aligned with a narrowed or tapered portion of the neck of the bottle 80 to allow more room for the user's hand. The handle opening 36 is also centered between bottles 36 longitudinally. FIG. 17 is an end view of the crate 10 and bottles 80. FIG. 18 is a top view of the crate 10 and bottles 80.

In use, a user can hold the upper handle portion 34 of the crate 10 in one hand while accessing the bottles 80 in the crate 10 with the other hand.

Generally, it is preferred that beverage crates 10 are dimensioned such that they can be arranged efficiently on a standard size pallet. Thus the ratio of the lengths of the end walls and the side walls is sometimes adjusted by making either of them thicker, such as by providing double-walls.

However, with the center structure 30 in the present crate 10, the dimension of the end walls can be adjusted by adjusting the width of the center structure 30. Thus, only single-walled end walls 16 and side walls 14 are necessary and the upper band portion 18 can have a constant width all around the crate 10.

In accordance with the provisions of the patent statutes and jurisprudence, exemplary configurations described above are considered to represent a preferred embodiment of the invention. However, it should be noted that the invention can be practiced otherwise than as specifically illustrated and described without departing from its spirit or scope.

What is claimed is:

1. A nestable crate comprising:
a base including a plurality of base walls, each of the plurality of base walls partially defining one of a plurality of bottle-receiving pockets;
a pair of opposed side walls extending upward from the base, each side wall including a plurality of side columns projecting into the crate to partially define the plurality of bottle-receiving pockets and connecting a side upper band portion to the base, each side upper band portion projecting outward of the crate relative to the side columns;
a pair of opposed end walls extending upward from the base, each end wall including a plurality of end columns projecting into the crate, each end column partially defining two of the plurality of bottle-receiving pockets, the plurality of end columns connecting an end upper band portion to the base, each end upper band portion projecting outward of the crate relative to the end columns; and
a center structure extending from one of the end walls to the other of the end walls, the center structure including a handle opening therethrough, the center structure including a plurality of center column portions extending down to the base, wherein the center structure divides the crate into two halves, each half having half of the bottle-receiving pockets, wherein the center structure is taller than the side walls and is receivable into an identical nestable crate nested thereon.
2. The nestable crate of claim 1 wherein the end columns each project inward to partially define at least two of the plurality of bottle-receiving pockets.
